US00D773683S

(12) **United States Design Patent** (10) Patent No.: **US D773,683 S**
(45) Date of Patent: ** Dec. 6, 2016

(54) **VESSEL**

- (71) Applicant: **TECTON DICKINSON AND COMPANY**, Franklin Lakes, NJ (US)
- (72) Inventors: **Melody M. H. Kuroda**, Durham, NC (US); **Michael Justin Lizzi**, Stewartstown, PA (US); **Thomas D. Haubert**, Columbus, OH (US); **Michael L. Marshall**, Lewis Center, OH (US); **James A. Prescott**, Columbus, OH (US); **M. Scott Ulrich**, Columbus, OH (US)
- (73) Assignee: **Becton, Dickinson and Company**, Franklin Lakes, NJ (US)
- (**) Term: **14 Years**
- (21) Appl. No.: **29/516,050**
- (22) Filed: **Jan. 29, 2015**

Related U.S. Application Data

- (63) Continuation of application No. 29/462,385, filed on Aug. 2, 2013, now Pat. No. Des. 724,754, which is a continuation of application No. 29/418,181, filed on Apr. 12, 2012, now Pat. No. Des. 690,826.
